UNITED STATES PATENT OFFICE.

GEORGE T. FULTON, OF GRAND ISLAND, NEBRASKA.

DESIGN FOR A TOY AEROPLANE.

58,078.

Specification for Design.

Patented June 7, 1921.

Application filed December 15, 1919. Serial No. 345,144. Term of patent 14 years.

To all whom it may concern:

Be it known that I, GEORGE T. FULTON, a citizen of the United States, and a resident of Grand Island, in the county of Hall and State of Nebraska, have invented new, original, and ornamental Designs for Toy Aeroplanes, of which the following is a specification.

My invention relates to an improvement in

designs for toy aeroplanes, in which, as shown by the drawing—

Figure 1 is a perspective view of my proposed design; and

Fig. 2 is a front view.

I claim:

The ornamental design for a toy aeroplane, as shown.

GEO. T. FULTON.
